CONTROL MECHANISM

Herbert E. Lindemann, Milwaukee, Wis., assignor
to Perflex Corporation, Milwaukee, Wis., a corporation of Wisconsin

Application September 19, 1938, Serial No. 230,723

26 Claims. (Cl. 200—83)

This invention relates in general to control mechanisms but more particularly to physical condition responsive controls such as are employed in air conditioning systems and the principal object of the invention is concerned with the production of a new and improved control mechanism adapted for heavy duty service.

A further object is to provide a control mechanism which is extremely sensitive and accurate in its response to variations in physical conditions over a wide range.

An additional object is to provide improved regulating means for a control mechanism whereby the operation of the device can be accurately predetermined.

A further object of the invention is to provide improved switch operating mechanism for automatic snap action switches.

Another object is to design a control mechanism which will be capable of directly handling line voltage loads through its switching mechanism for controlling motors and other apparatus without the use of a relay.

Another object is to provide a snap acting switch mechanism including elements which can be arranged to either open or close the switch contacts upon a movement of the switch actuator in a given direction.

Other objects and advantages reside in certain novel features of construction, arrangement and combination of the parts which will be hereinafter more fully described and particularly pointed out in the appended claims. It has been chosen by way of example to illustrate and describe the invention in connection with a physical condition responsive mechanism such as a room thermostat in which a charged bellows is utilized as the controlling medium. In another of its forms the control mechanism may be arranged to respond to humidity, pressure, or other physical conditions.

A preferred embodiment of the control mechanism will now be described in connection with the accompanying drawings in which:

Fig. 1 is a front elevation of the control mechanism;

Fig. 2 is a side view of the device with the cover in section;

Fig. 3 is a sectional side view taken along the line 3—3 of Fig. 1;

Fig. 4 is a fragmentary view of the top portion of the device;

Fig. 5 is a full rear elevation of the control device;

Fig. 6 is a top view with the cover in section;

Fig. 7 is a bottom view with the cover removed; Fig. 8 is another bottom view with the switching elements shown in closed position.

Fig. 9 is a view of the adjusting elements shown in extended perspective relationship;

Fig. 10 is a side view of a portion of a modified construction in which the switching elements are normally closed;

Fig. 11 is an end view of the modification; 10 while

Fig. 12 is a fragmentary bottom portion of Fig. 1 with the operating arm removed.

In its preferred form the control mechanism comprises a rectangular base 5, preferably formed of some molded insulation product having a shallow depression 6 formed in its front surface. On the rear side a flange 7 extends around the surface of the base and forms a depression 8 so that the various terminal and mounting screws are protected by the flange 7 when the instrument is mounted in place. The device is usually supported on a flat wall surface (not shown) and is provided with bosses or projecting portions 9 and 10 for engaging the wall or a mounting plate (not shown) fastened to the wall. Mounting screws 11 and 12 extend from the front side of the base 5 and are adapted to thread into the mounting plate. The bosses 9 and 10 are arranged so that the elements on the base are not subjected to strains or stresses caused by uneven wall surfaces.

A U-shaped metal bracket 13 (see Fig. 9) is secured to the base 5 in the depression 6 by means of a pair of supporting screws 14 (Fig. 35) threaded from the rear side of the base. The bracket 13 is provided with outwardly projecting arm portions 15 and 16 to which are attached steel spring hinges 17 and 18 respectively. A relatively stiff operating arm 19 is arranged 40 parallel to the base 5 and has one end riveted to the other ends of the spring hinges 17 and 18 so that the operating arm is pivoted by means of these hinges. By providing this spring hinge type of construction for pivoting the arm 19 the control operates with greater accuracy and sensitivity due to the fact that no lost motion or loose connections are present. For the purpose of actuating the operating arm 19 a physical condition responsive means shown here in the form of a thermostatic element or bellows 21, is provided. This bellows 21 is filled with a highly volatile gas or liquid which has the inherent quality of expanding and contracting with changes in temperature of the surrounding air. 50 Upon expanding due to a temperature rise it

moves the free end of the operating arm 19 in a direction away from the base. The bellows 21 is provided at its lower end as shown in Fig. 3, with a small tube 22 which extends into a cylindrical projection 23 formed in the base 5. A hollow metal stud 24 surrounds the tube 22 and forms a connecting link for supporting the bottom of the bellows on the projection 23 with its axis perpendicular to the base. This projection 23 also serves to thermally insulate the bellows from the base. After the expandable medium is placed within the bellows the end of tube 22 is sealed. At its outer end the bellows 21 has a pivot pin 25 soldered to it which engages the hollowed out surface of a stud 26 riveted near the pivoted end of the operating arm 19 as shown. By connecting the bellows substantially adjacent the fulcrum point of the arm 19, the arm multiplies the motion of the bellows in a large ratio, and consequently it is moved with very slight motion of the bellows.

A connecting lever 27 for adjusting the operating range of the thermostat is pivoted by pin 28 to a pair of small bracket ears 29 formed in bracket 13. The lower end of this connecting lever 27 is connected to a stiffly tensioned coil spring 31 arranged perpendicularly to the base and the other end of which is threaded around an adjusting stud 32. Stud 32 in turn is held to the operating arm 19 by a calibration adjusting screw 33. Screw 33 is arranged between the ends of the arm 19, and turning it adjusts the tension of coil spring 31 any desired amount for calibration purposes as will be pointed out.

The free end of operating arm 19 has an insulating block 34 attached to it by means of supporting screws 35 and the other end of the block 34 has an armature and movable contact bracket 36 secured to it by the screws 37. The bracket 36 is bent in the shape shown with two parallel offset surfaces connected by an angular portion so that the surfaces are on different planes. It is movable together with the operating arm 19 in a direction away from and towards the base. In order to limit the outward movement of the operating arm 19 beyond a fixed point, a stop bracket 38 is provided which is secured by screw 39 to the base 5. A projecting stop portion 41 formed in one end of the armature bracket 36 engages a slot in the stop bracket 38 for the purpose stated.

A magnetic armature 42 is formed on the end of bracket 36 and is arranged with a pair of outwardly extended ear portions 43. These ears provide a means for pivoting a rigid bar or connecting arm 44 through the medium of a pivoting pin 45 extending through ear portions 43 and similar extensions formed on rigid bar 44. A flexible contact arm 46 is arranged at one side of bar 44 (see Fig. 7) and is riveted at 47 to the rigid bar 44. A contact point 48 is riveted to rigid bar 44 and flexible arm 46. A second contact point 49 is secured to the free end of the flexible arm 46 but is slightly separated from the bar 44 because the free end of bar 44 is offset from flexible arm 46. With the foregoing construction and arrangement of elements it is seen that movement of the end of operating arm 19 results in the contact points 48 and 49 being moved in a direction perpendicular to the base. Arranged on the base in operative relation to movable contact points 48 and 49 are fixed contact points 51 and 52. Fixed contact point 51 is supported on the end of an adjustable contact stud 53 which threads into the top of a contact supporting bracket 54. A slot is cut in the top of contact

bracket 54 (see Fig. 12) where the stud 53 is threaded, in order that the threads of the stud may be resiliently and tightly gripped and thereby hold the stud in its adjusted position. The contact bracket 54 extends through the base 5 to the rear side thereof where it is secured by a pair of screws 55 threaded into a bottom portion of the contact bracket from the front of the base. A terminal screw 56 also threads into bracket 54 at the rear of the base and provides a means for the attachment of a connecting wire (not shown). The other contact point 52 is arranged in a similar manner with contact stud 57 threaded into the split top portion of supporting contact bracket 58 which in turn is secured to the base by means of supporting screws 59. At the rear side of the base a terminal screw 61 threads into contact bracket 58 for the connection of an electrical wire (not shown).

The stud 57 is provided with a lug 62 (Fig. 12) having a screw driver slot therein for the purpose of adjusting the differential of the control device as will be hereinafter pointed out. Lug 62 is arranged to cooperate with the scale markings 63 stamped upon the top of contact bracket 58. The top of stud 53 is provided with a hexagonal head portion to facilitate turning the stud so that the height of contact 51 may be varied with respect to the base.

Arranged between the two sets of contact points and adjacent the armature 42 is a permanent horseshoe magnet 64. It is supported by a washer and clamping screw 65 (see Fig. 3) threaded into supporting bracket 66 which in turn is mounted upon the base by a pair of screws 67 threaded from the rear of the base 5. The poles of magnet 64 are arranged so as to influence the armature 42 to assist in providing snap action to the opening and closing of the contact points.

At the upper end of the base 5 a cam disc 68 is positioned. It is preferably molded of some suitable insulation product and arranged to be rotatable about an axis perpendicular to the base 5. It is provided with a spiral cam surface 69 on its front surface as best seen in Fig. 3. An aperture 70 in the base 5 (see Fig. 9) provides a bearing surface for a brass stud 71 molded into and extending from the rear side of cam disc 68. A circular groove 72 is formed near the end of stud 71 and is engaged at the rear of base 5 by the forked end of a tensioned leaf spring 73. Spring 73 in turn is secured to the rear side of the base by a pair of screws 74. The upper end of the spring 73 is flexed away from the base in order that it may resiliently hold the cam disc 68 in frictional engagement with the depressed portion 6 in the front side of the base. A narrow circular bearing surface 75 on the rear of the cam disc engages the base for this purpose.

An adjustable number dial 76 is provided at the rear of the cam disc 68. It has a knurled periphery in order to facilitate manual manipulation of the same and also a series of temperature indicating numerals stamped on its front surface as shown. The number dial 76 has a large opening in its center together with a slot 77 cut in the side of the opening. A stop member 78 formed in the rear side of the cam disc 68 extends through the slot 77 so that whenever number dial 76 is rotated the cam disc 68 is likewise rotated. A dish shaped spring washer 79 is positioned between the front of the number disc 76 and the rear side of cam disc 68 so that it closely embraces the outside of the bearing surface portion 75. The purpose of this spring wash-

er 79 is to prevent binding or straining the cam disc 75 in its adjusted position and also to prevent the number dial 76 from loosely rattling in its position since the washer tends to resiliently urge both discs apart.

A pair of stepped shoulder portions 81 and 82 are formed upon the upper front surface of the base and serve as a bearing surface for the number dial when it is rotated. The rotary position of number dial 76 is limited in either direction by the stop 78 on cam disc 68 which extends through notch 77 and engages notches 83 cut in the bracket 13 as shown in Fig. 9. It is occasionally desirable, for the purpose of preventing unauthorized manipulation of the number dial 76, that the dial be locked in a particular set position. For this purpose a clamping member 84 (Fig. 1) is provided which engages the front side of number dial 76 and clamps the dial tightly to the base surface 82 when clamping screw 85 is tightened on it. Due to the fact that the number dial 76 is not rigidly connected to cam disc 68 this clamping arrangement will not disturb the adjustment of cam disc 68.

The upper end of pivoted connecting lever 27 is provided with a small cylinder 86 which is riveted to the lever 27 so that it cannot rotate. This cylinder 86 is arranged to bear upon the cam surface 69 due to the tension of the coiled spring 31 and rides along the cam surface whenever dial 76 is rotated. The cylinder 86 is positioned so as to lie directly on a radial line extending through the axis of the cam disc 68 and because of its rigid connection with the lever 27 it will always bear with the same point of contact upon the cam and thereby enable the calibration of the instrument to be maintained at a constant uniform value regardless of the position to which the cam disc is rotated.

It is desirable that the various elements of the instrument be protected from injury and for this purpose a metal cover 87 is provided. As seen in Fig. 5 a number of reinforcing ribs 88 are formed around the insides of the cover which engage the base 5 and space the cover from it. The bottom of the base 5 is provided with a pair of projections 89 while at the top of the base a pair of resilient metal clips 91 and 92 are secured thereto and extend outward therefrom. In placing the cover upon the base these clips 91 and 92 first engage the top cover members 88 and are then forced tightly into engagement therewith by the projections 89 on the bottom of the base engaging the ribs 88 on the cover. In this manner the cover is resiliently held to the base so it will not be loose or tend to rattle. Likewise, all stresses and strains on the elements mounted on the base are eliminated. In order that the cover may be locked to the base a cover screw 93 is provided which engages a slot in the cover and is threaded into the base through an enlarged portion of the slot so that it is flush with the bottom surface of the cover. The cover 87 as seen in Figs. 4 and 6 surrounds the front and sides of the instrument but is open at the top and bottom to permit the surrounding air to circulate therethrough and contact the bellows. A series of grills 94 are provided across the openings to protect the internal mechanism. A pointer or indicator 95 is likewise formed in the top of the cover in order to indicate the setting of the number dial 76.

Referring now particularly to Fig. 2 the cover 87 is provided on its front surface with a scale plate 96 having the usual temperature gradua-

tions marked thereon. The scale plate 96 is arranged so that its lower end rests in a slot 97 formed on the front of the cover 87. The usual thermometer 98 is arranged behind an opening 5 in scale plate 96 and is resiliently held in place by a thermometer guard strip 99 which has an enlarged portion 101 for accommodating the thermometer bulb and also imparting greater resiliency to the strip. The upper end of the thermometer 98 is suitably sealed into an opening in the strip 99. At its upper end thermometer guard 99 is slotted and a clamping screw 102 passes through the slot and a hole in the cover and threads into the upper end of scale plate 96. At the bottom a clamping screw 103 passes through a slotted opening in thermometer guard 99 and threads into the cover. By merely loosening screws 102 and 103 the thermometer strip 99 and likewise the thermometer 98 may be moved up or down in order to calibrate it to agree with the readings on the scale plate 96. This arrangement likewise facilitates the assembly of the aforesaid elements upon the cover.

The manner in which the various calibrating adjustments for the control mechanism are made will now be pointed out. In the initial calibration of the device the instrument is first placed in a testing room where the temperature is maintained at 70 degrees F. The dial 76 is then rotated until the numerical indication "60" is positioned opposite the center one of the graduations 106 marked on the upper end of the base and at which time the designation "70" will be directly on top of the dial and opposite pointer 95 if the cover were on. The calibration adjusting screw 33 is then turned to vary the tension of spring 31 until the operating arm 19 just closes the contacts at the setting made. The instrument is now set to operate and close the contacts at any temperature indication to which the dial 76 is rotated with respect to pointer 95.

The differential of the device is the change in temperature necessary to cause the bellows to open and close the contacts. To calibrate this 45 differential initially the studs 53 and 57 are adjusted to give a small clearance between the armature 42 and magnet 64 with the contacts closed. The lug 62 is left with its screw driver slot at minimum differential setting on the scale 50 markings 63 and the other stud 53 adjusted to vary the air gap until the correct differential of one or more degrees is obtained. After this 55 calibration the lug 62 may be subsequently rotated across scale 63 to any of the markings to lessen the air gap between the armature and magnet and thereby increase the pull of the magnet so that the differential is widened.

The construction and arrangement of the various elements constituting the thermostatic switch having been pointed out in detail, their operation 60 will now be explained. Assume for example, that the number dial 76 has been rotated to a position such that the temperature indication of 77 degrees has been placed directly on top of the instrument as shown in Fig. 1. Cam disc 69 is accordingly positioned so as to tilt the adjusting lever 27 a certain amount by means of cylinder 86 riding on the cam surface. Assume likewise that the thermostatic switch has been located in a room so as to maintain the temperature of the same at about 77 degrees. As the temperature of the room drops the bellows fluid reduces its vapor pressure in definite relation to the temperature, and the force exerted against the operating 65 arm 19 by the bellows diminishes, causing the

operating arm 19 to move under the combined efforts of the spring 31 and the magnet 36 toward the magnet until equilibrium of the forces is again established. As the operating arm moves toward the magnet in this manner due to reduction in temperature, a point is reached whereupon further motion of the operating arm 19, the magnetic effort is greater than the opposing effort of the spring and bellows assembly (referred to the same point on the arm 19), and an unstable state is established. At this time the operating arm 19 snaps over toward the magnet, closing the contacts 48 and 52, and 49 and 51 respectively, with snap action, and the unbalance force between the magnet, and the bellows and spring assembly, is applied to the contacts. The closing of the contacts effects the control of the heating plant whereby an increase or rise of temperature takes place within the room containing the thermostat.

As the temperature of the room rises, the bellows fluid increases its vapor pressure in relation to the temperature and the force exerted against the operating arm 19 by the bellows increases. When the bellows temperature reaches 77 degrees plus the differential for which the instrument is set, the bellows effort just exceeds the opposing spring and magnetic efforts and the arm 19 snaps outward. Since the magnetic effort drops much more rapidly than the spring and bellows assembly forces as the arm 19 moves outward, the unbalance force on the arm 19 becomes quite large after a short amount of travel and considerable acceleration is imparted to the arm and movable assembly, causing it to move and open the contacts with a fast snap action.

Returning now to the action taking place as the contacts are closed, the movable contact 49 on the free end of resilient arm 46 engages its associated fixed contact 51 and a slight wiping action takes place until the rigid bar 44 engages the rear end of contact 49. The other movable contact 48 engages the fixed contact 52 with a wiping action due to the leveling effect produced by the pivot 45. As seen clearly in Fig. 8 which shows the contacts in their closed position, magnet 64 maintains armature 42 within its influence without touching the same because it is held away from it by the contacts engaging each other. Due to this magnetic attraction the contacts are not subjected to vibration or shock but are held tightly in intimate engagement. The resilient arm 46 forms an electrical bridge circuit which extends from a connecting wire (not shown) attached to terminal screw 56, through contact plate 54, contact stud 53, contacts 51 and 49, resilient arm 46, contacts 48 and 52, stud 57, contact plate 58 to the other terminal screw 61 and a wire attached thereto. Due to the poor contact between rigid bar 44 and the rear of contact 49 most of the current flows through the flexible arm 46.

When the contacts are opened by the operating arm 19, the bellows exerts its force against the combined tension of spring 31 and the pull of the magnet. When a point is reached shortly beyond the balance of effort between these elements the armature 42 rapidly moves away from the influence of the magnet. Because of the resiliency of flexible arm 46 and the time it takes for the end of rigid bar 44 to move away from the rear side of the contact 48, the contacts remain closed for a short interval of time after the aforesaid balance of effort has been passed and open after

the rigid bar 44 has had time to accelerate. In this manner the contacts are separated with a distinctive snap action.

By providing this snap action corrosion, arcing and pitting of the contacts is obviated. The device operates more accurately and positively without fluttering of the contacts and should there be any tendency for the contacts to stick or become slightly welded together, they are immediately separated due to the pivotal arrangement of the rigid arm 44 which acts to pry them apart. Also because of the fact that it is only necessary to open one set of contacts to interrupt the bridge circuit controlled by the instrument, either set of contacts may remain lightly in engagement with the associated fixed contact in case the instrument is not mounted in a level position. The foregoing advantages render the device suitable for handling relatively high loads without the use of relays.

In the construction described the elements of the control device are such that the contacts are closed upon a drop in room temperature and are opened when the temperature drops as pointed out. It is occasionally desirable that this arrangement be reversed so that the contacts will be closed upon a temperature rise and opened upon a fall in temperature, such as in a refrigeration system for example. This reverse operation may be easily and conveniently accomplished in the instant arrangement as shown in the modifications Figs. 10 and 11. The screws 37 are merely removed, the armature bracket 36 reversed, and the screws inserted and tightened again so that the armature bracket extends towards the base. The contact points 48 and 49 now extend upwardly into engagement with the bottom of studs 53 and 57 which are provided at this point with contact points 104 and 105. The magnet clamping screw 65 is likewise loosened to permit the magnet 64 to be rotated 180° so that its poles extend toward the base in operative relation to the armature 42 as shown. Clamping screw 65 is then tightened to hold the magnet in this position. The armature bracket 36 is so shaped that it comprises two parallel flat portions arranged in different planes, offset from one another and connected by an angular flat portion between the ends. The portion of the bracket connected to the block 34 by screws 37 is arranged on a plane which is substantially on a line with the top surfaces of the contact brackets 54 and 58 and therefore at the approximate center point between the studs 53 and 57. This arrangement it is seen permits the armature end of the bracket 36 to be placed in association with either end of the contact studs to operate the contacts, without the necessity of bending the same or of adjusting the studs to different elevations from the base to accommodate the bracket. It is therefore seen that without the introduction of any auxiliary elements or new parts the control device is arranged for universal adaption in which a different control may be effected by merely reversing certain elements.

It is sometimes necessary that the manual manipulation of the number dial 76 be limited so that the mechanism cannot exercise its control either beyond or below a maximum or minimum temperature value. To provide for this limitation a stop 107 is formed on the number dial 76 at any point where it is required. As shown in Fig. 1 the stop 107 engages the clamping member 84 when the dial 76 is rotated to a temperature reading of about 77 degrees. The

stop 101 prevents any movement of the dial beyond this point.

Contributing factors to the ability of the device to control heavy loads and yet operate on small temperature changes are the following: A high sealing effort or arresting force is obtained which prevents the contacts from bouncing after they have made contact. Lost motion in the operating beam is prevented by the use of spring hinges. Unwanted flexure of the beam support 10 15 is prevented, although lightweight supports are used, by the method of mounting the bellows perpendicular to the base to allow the use of a support which is stressed principally in tension.

A contributing factor to the ability of the device to respond to temperature changes without appreciable time lag is the construction and mounting of the bellows. The bellows 21 is constructed with a very low ratio of mass to exposed surface area in order to minimize the heat capacity, and is connected to the rest of the mechanism through members 24 and 25 of small cross sectional area to minimize the heat transfer.

From the foregoing description of the invention it is apparent that a novel type of control mechanism has been designed in which the elements thereof are compactly arranged, easy to assemble and adjust, and in which relatively heavy loads are readily controlled.

Since only a preferred illustration of the invention has been disclosed it is conceivable that modifications thereof may be readily perceived by those well versed in the art and it is therefore desired that the invention be not limited to the precise structure illustrated and described, but only to the extent of the appended claims.

What is claimed is:

1. A control mechanism of the class described comprising a base, an operating arm arranged parallel to the base, means for effecting movement of said operating arm perpendicular to the base and in two directions, an armature bracket secured to but insulated from said operating arm and having an armature on the end thereof, a pair of movable contacts, connecting arm means supporting one of the movable contacts from each end thereof, means on the armature for pivotally supporting the connecting arm means between its ends, a pair of fixed contacts arranged in operative relation to said movable contacts and engageable therewith responsive to the movement of the operating arm, a magnet arranged on the base between the contacts and in operative relation to the armature for providing snap action to the engagement of said contacts, the engagement of said contacts preventing the actual engagement of the armature with the magnet, and a stop on the base engaged by the armature bracket for limiting the movement of the operating arm when the contacts are disengaged.

2. A control mechanism of the class described comprising a supporting base, an operating arm pivoted to the base and arranged parallel thereto, an armature carried at one end of the operating arm and arranged parallel to the base, means for insulating said armature from the arm, a permanent magnet supported on the base in a position to influence the armature, connecting arm means pivoted to the armature, a movable contact carried on each end of the connecting arm means and arranged with the armature between them, a pair of fixed contacts supported on the base in operative relation to the movable

70 contacts and arranged with the magnet between them, resilient physical condition responsive means arranged between the base and the operating arm at a point near the pivot of the operating arm for actuating the operating arm in one direction, different resilient means also arranged between the base and the operating arm at a point near the armature end of the operating arm for actuating the operating arm in another direction, both of said resilient means assisting the magnet to impart snap action to the opening and closing of the control contacts, and means for adjusting both of said resilient means.

3. A control mechanism of the class described comprising an elongated base, a physical condition responsive element arranged upon said base at one end thereof, a supporting bracket arranged at the same end of the base, an operating arm having one end hingedly supported from the bracket and having its free end extending toward the opposite end of the base, a control element carried by the free end of the operating arm, a fixed control element on the base arranged in cooperative relation to said first control element, means for associating said physical condition element with said operating arm adjacent the hinged end of the arm whereby the operation of the physical condition responsive element effects the cooperation of the control elements, an adjustable cam rotatively mounted upon the base adjacent the hinged end of the operating arm for adjusting the point at which the condition responsive element is effective to bring about the cooperation of the control elements, an adjustable tension spring connected to the operating arm at a point between its hinged end and its free end, a connecting lever pivoted to the base and having one end connected to the tension spring and the other end in slidable engagement with said adjustable cam, and means for imparting snap action to the operation of the control elements.

4. A control mechanism of the class described comprising a base, an operating arm spaced from the base and arranged parallel thereto, means for hinging the operating arm to the base, a bellows secured at one end to the base and having its other end associated with the operating arm adjacent its hinge for actuating the same, a spring acting upon the operating arm, means on the arm for calibrating the tension of the spring, rotatable adjustment means secured to the base, means connecting the adjustment means with the other end of the spring whereby the bellows may be adjusted to predetermine its movement of the operating arm, a contact bracket carried by the operating arm, movable contacts on the contact bracket, fixed contacts on the base in operative relation to the movable contacts, means including the bellows and the spring for imparting snap action to the opening and closing of the contacts, and means associated with the fixed contacts for adjusting the differential operation of the operating arm.

5. A control mechanism of the class described comprising an elongated base, a U-shaped bracket supported at one end of the base, an operating arm arranged in spaced parallel relationship to the base, means for hingedly supporting the operating arm on the U-shaped bracket, an expandable and contractible bellows supported at one of its ends from the base and having its axis arranged perpendicular thereto, means for associating the other end of the bellows with the operating arm adjacent its hinge support to actuate the arm in one direction of

movement, a connecting lever pivoted to the U-shaped bracket adjacent the bellows support, a tension spring arranged perpendicular to the base and connected between one end of the lever and a point intermediate the ends of the operating arm for moving the operating arm in another direction, a manually rotatable disc arranged on the base adjacent the U-shaped bracket with its axis extending perpendicular to the base, a spiral cam on said disc responsive to the rotation of the disc for adjustably moving the other end of the connecting lever to vary the tension of the tension spring, cooperable means on the disc and the U-shaped bracket for limiting the rotative movement of the disc, cooperable contact points supported on the operating arm and on the base and actuated by the movement of the arm, and cooperable magnetic means also supported on the movable end of the operating arm and on the base for imparting snap action to the actuation of the contact points.

6. A control mechanism of the class described comprising a supporting base, an operating arm arranged parallel to the base, means for pivoting said operating arm to the base, a bellows arranged between the base and the operating arm with its axis perpendicular to the base and having one end supported on the base and the other end associated with the operating arm near its hinge, said bellows adapted to move the operating arm in one direction, an armature bracket carried by said operating arm and having an armature element formed thereon arranged parallel with the base, a pair of movable contacts supported on the armature bracket, a pair of fixed contacts arranged on the base in operative relation to the movable contacts, a spring arranged with its axis perpendicular to the base and connected at one end to the operating arm at a point on the arm between the bellows connection and the armature bracket, said spring effective to move the arm in another direction, a connecting lever pivoted intermediate its ends to the base and having each end movable perpendicular to the base, one end of said lever being connected to the other end of said spring whereby its tension is adjusted by the movement of the lever, a spiral adjusting cam rotatably supported on the base with its axis perpendicular thereto for moving the other end of the connecting lever, and magnetic means supported on the base in operative relation to the armature for providing snap action to the operation of said contacts, said movable contacts bridging said fixed contacts to complete an electrical circuit.

7. A control mechanism of the class described comprising an elongated base, a U-shaped supporting bracket secured to one end of the base and having the two legs extending outwardly therefrom, an operating arm arranged parallel to the base, hinge means connecting the operating arm with the bracket legs, an armature bracket carried by the operating arm and arranged parallel to the base, a rigid bar pivoted at its mid-point to said armature bracket and arranged at right angles thereto, a flexible arm secured to one end of the rigid bar and arranged between the rigid bar and the armature bracket, the other end of the flexible arm being spaced apart from the rigid bar, a pair of spaced movable contact points secured to opposite ends of the flexible arm, a pair of fixed contact points supported on the base in operative relation to the movable contact points, a magnet supported on the base between the fixed contacts for influ-

encing the armature bracket to impart snap action to the operation of the contacts, a physical condition responsive element having its axis arranged perpendicular to the base and secured at one end thereto and at the other end cooperating with the operating arm adjacent its pivot for actuating the same, a connecting lever pivoted at its mid-point to the supporting bracket adjacent the condition responsive element, a coiled spring arranged with its axis perpendicular to the base and connected at one end with the connecting lever and at the other end with the operating arm at a point between the condition responsive element and the armature bracket, the connection of the spring with the operating arm comprising an adjusting means for calibrating the tension of the spring, a manually rotatable dial having a spiral cam thereon arranged on the base adjacent the supporting bracket with its axis perpendicular to the base, means on the supporting bracket for limiting the rotation of the dial in either direction, the other end of the connecting lever having slidible engagement with the spiral cam whereby the operation of the contacts can be predetermined in accordance with physical condition changes, and locking means on the base adapted to engage the rotatable dial to prevent manual rotation of the same.

8. A control mechanism of the class described comprising a supporting base, an operating arm, means for hingedly supporting the operating arm to the base, means on the base and associated with the operating arm for moving it in either of two directions, an armature bracket carried by the operating arm and having an armature formed on the end thereof, switch mechanism comprising movable contacts supported by said armature bracket on each side of the armature and fixed contacts supported on the base, a reversible magnet on the base, in operative relation to the armature for influencing the same and for rendering the switch mechanism snap acting, said fixed and said movable contacts arranged to move toward engagement and said armature toward said magnet responsive to the movement of the operating arm in a direction toward the base, said armature bracket arranged to be reversible on its support to effect disengagement of the contacts responsive to the same movement of the operating arm in a direction toward the base when said magnet is reversed.

9. A control mechanism of the class described comprising a base, an operating arm pivoted on the base, an armature bracket carried by the arm, means on the base for moving the arm in a direction either away from or toward the base, movable switching mechanism carried by said armature bracket, fixed switching mechanism supported on the base in operative relation to the movable switching mechanism, said switching mechanism adapted to move into engagement responsive to the movement of the operating arm toward the base, and magnetic means associated with said switch mechanism for rendering the switch mechanism snap acting, said armature bracket adapted to be reversed to open said switching mechanism when the operating arm is moved in a direction toward the base.

10. A control mechanism of the class described comprising a base, an operating arm pivoted to the base, a physical condition responsive element controlling the movement of the operating arm, a pair of fixed contact supports secured to the base and having raised portions arranged parallel to the base, a contact stud extending through

the raised portion of each contact support, a reversible contact bracket, movable contacts pivotally carried by the reversible contact bracket in operative relation to the contact studs, means for supporting the reversible contact bracket in one manner from the end of the operating arm whereby the movable contacts are moved into association with one end of the contact studs, said means adapted to support the reversible contact bracket in another manner from the operating arm whereby the movable contacts are moved into association with the other end of the contact studs, and means associated with said reversible contact bracket for rendering the contacts snap acting.

11. A control mechanism of the class described comprising a base, an operating arm pivoted to the base, a physical condition responsive element controlling the movement of the operating arm, a pair of fixed contact brackets secured to the base each having a raised portion arranged parallel to the base, a separate contact stud extending through the raised portion of each fixed contact bracket, a movable contact bracket, means for supporting the movable contact bracket from the movable end of the operating arm, a pair of movable contacts pivotally carried by the movable contact bracket in operative relation to the contact studs, said movable contact bracket arranged for mounting in either of two positions on the operating arm whereby the movable contacts can be made to engage either ends of the contact studs and thereby either open or close the contacts on a given change in the physical condition, and means associated with said removable contact bracket for rendering the contacts snap acting.

12. A control mechanism of the class described comprising a base, an operating arm pivoted to the base, a physical condition responsive element controlling the movement of the operating arm, a pair of fixed contact supports secured to the base and having raised portions arranged parallel to the base, a contact stud extending through the raised portion of each contact support, a movable contact bracket having two parallel flat portions offset from one another and connected by an angular extending portion, a pair of movable contacts pivotally supported on one of the flat portions of the bracket, means for supporting the other of the flat portions of the bracket on the arm in a position substantially on a plane with the raised portions of the contact supports whereby the movable contacts are adapted to be moved by the bracket into association with one end of the contact studs, said bracket arranged to be reversed on its supporting means whereby the movable contacts are adapted to be moved into association with the other end of the contact studs, and means associated with said reversed contact bracket for rendering the contacts snap acting.

13. A device of the class described comprising a base, an operating arm, means for hingedly supporting the operating arm on the base, flexible physical condition responsive means for moving the operating arm in one direction, an adjustable flexible means opposing the action of the physical condition responsive means for moving the operating arm in a reverse direction, means on the base remote from the adjustable flexible means for adjusting the same, lever means pivoted on the base connecting the adjustable flexible means to the adjusting means for applying effort produced by the remotely located adjusting means

5 to the adjustable flexible means, and means on the base for magnetically biasing the operating arm, said flexible physical condition responsive means, said adjustable flexible means and said magnetic means cooperating to render said operating arm snap acting in either direction without interposing lost motion.

14. A device of the class described comprising a base, an operating arm, control mechanism actuated by the operating arm, means for hingedly supporting the operating arm on the base, flexible physical condition responsive means for moving the operating arm in one direction, adjustable flexible means opposing the action of the physical condition responsive means for moving the operating arm in a reverse direction and for adjusting the device to predetermine the physical condition at which the control mechanism is actuated, means on the base remote from the adjustable flexible means for adjusting the same, lever means pivoted on the base connecting the adjustable flexible means to the adjusting means for applying effort produced by the remotely located adjusting means to the adjustable flexible means and for reversing the direction of the applied effort, and means on the base for magnetically biasing the operating arm, said flexible physical condition responsive means and said adjustable flexible means being connected to said operating arm in a manner to eliminate lost motion between the operating arm and both flexible means, said physical condition responsive means and said adjustable flexible means additionally cooperating with the magnetic biasing means for rendering the operating arm snap acting in either direction.

15. A device of the class described comprising a base, an operating arm, control mechanism actuated by the operating arm, means for hingedly supporting the operating arm on the base, flexible physical condition responsive means arranged perpendicular to the base and fixed thereto at one end for moving the operating arm in one direction, the other end of said physical condition responsive means engaging the operating arm near the axis of rotation of the operating arm, adjustable flexible means opposing the action of the physical condition responsive means for moving the operating arm in a reverse direction and for adjusting the device to predetermine the physical condition at which the control mechanism is actuated, said adjustable flexible means being connected to the operating arm at a point more remote from its axis of rotation than the point of engagement of the physical condition responsive means, means on the top front surface of the base remote from the adjustable flexible means for adjusting the same, lever means pivoted on the base connecting the adjustable flexible means to the adjusting means for applying effort produced by the adjusting means to the adjustable flexible means and for reversing the direction of the applied effort, and means on the base for magnetically biasing the operating arm, said flexible physical condition responsive means and said adjustable flexible means being connected to said operating arm in a manner to eliminate lost motion between the operating arm and both flexible means, said physical condition responsive means and said adjustable flexible means additionally cooperating with the magnetic biasing means to render the operating arm snap acting in either direction.

16. A control mechanism of the class described

comprising a base, an operating arm arranged parallel to the base, an expansible and contractible bellows supported at one end on the base and having its axis perpendicularly disposed thereon, the other end of the bellows connecting with the operating arm for transmitting movement thereto, an adjustable dial having indicia thereon rotatably supported on the base with its axis of rotation perpendicular to the base, a cover for the mechanism, said dial arranged to protrude through the cover to render the indicia readable and the dial accessible for adjustment, a connecting lever pivoted to the base, means on the adjustable dial for moving one end of the connecting lever, a coil spring having its axis perpendicularly disposed with respect to the base connecting the other end of the lever with the operating arm at a point more remote from the connection thereto of the expansible and contractible bellows, and means for magnetically biasing the operating arm whereby snap action of the operating arm is obtained by the sole cooperative action of the resiliency of the expansible and contractible means and coil spring with the magnetic biasing means.

17. A device of the class described comprising a base, an operating arm, control mechanism actuated by the operating arm, means for hingedly supporting the operating arm to the base, flexible physical condition responsive means for moving the operating arm in one direction, adjustable flexible means opposing the action of the physical condition responsive means for moving the operating arm in a reverse direction and for adjusting the device to predetermine the physical condition at which the control mechanism is actuated, a rotary cam on the front of the base remote from the adjustable flexible means for adjusting the same, a dial having indicia thereon for rotating the spiral cam, a cover for the device, said dial arranged to protrude through the cover to render the indicia readable and the dial accessible for adjustment, lever means pivoted on the base connecting the adjustable flexible means to the spiral cam for applying effort produced by the spiral cam to the adjustable flexible means, and means on the base for magnetically biasing the operating arm, said flexible physical condition responsive means and said adjustable flexible means being connected to said operating arm in a manner to eliminate lost motion between the operating arm and both flexible means, said physical condition responsive means and said adjustable flexible means additionally cooperating with the magnetic biasing means to render the operating arm snap acting in either direction.

18. A control mechanism of the class described comprising, a base, a supporting bracket secured at one end of the base and having two legs extending outwardly therefrom, an operating arm arranged parallel to the base, spring means for hinging the operating arm upon each of the two legs, means for actuating the operating arm in one direction, lever means having one of its ends arranged to adjust the actuating means, an extension on the supporting bracket having two bracket ears for pivotally supporting the lever means, adjusting means on the base cooperating with the other end of the lever means, said supporting bracket having a pair of notches cut therein, and a stop on the adjusting means engaging the notches to limit the extent of motion of the adjusting means.

19. A control mechanism of the class described comprising a base, an operating arm pivoted to

the base, a cylindrical bellows responsive to physical conditions for motivating the operating arm, said bellows having a number of convolutions extending around its periphery for rendering the bellows flexible and for providing a large surface for contact with air surrounding the bellows, pivot means fastened to one end of the bellows for engaging the operating arm, a pedestal support on the base having an aperture therein, a tube fastened to the other end of the bellows providing a means for filling the bellows, said tube additionally serving to align the bellows with the pedestal support by projecting into said aperture, and a hollow metal stud around the tube arranged between the bellows and the pedestal support for spacing the bellows from the pedestal support and for assisting in the alignment of the bellows therewith, said pivot means and said pedestal support being arranged so as to substantially isolate the bellows from the remainder of the mechanism.

20. A control mechanism comprising a base, a stationary contact bracket mounted on said base, said bracket being formed so that a contact surface may be disposed on either side of said bracket, an operating arm mounted on said base and terminating short of said bracket, said operating arm oscillating laterally of said bracket, a movable contact bracket attached to said operating arm and carrying a movable contact cooperating with a stationary contact on said stationary contact bracket, an armature carried by said movable contact bracket, said movable contact bracket being reversible upon said operating arm for reversing said movable contact and armature, the movable contact and armature then being located at the opposite side of said stationary contact bracket from their previous positions, a magnet adapted to cooperate with said armature to provide snap action movement of said movable contact, and reversible mounting means for said magnet arranged to position said magnet for cooperation with said armature in either of its positions.

21. A control mechanism comprising a base, a stationary contact bracket mounted on said base, said bracket being formed so that a contact surface may be disposed on either side of said bracket, an operating arm mounted on said base and terminating short of said bracket, said operating arm oscillating laterally of said bracket, a detachable contact bracket mounted on the operating arm and carrying a movable contact cooperating with a stationary contact on said stationary contact bracket, an armature carried by said detachable contact bracket, a magnet adapted to cooperate with said armature to provide snap action movement of the movable contact, and reversible mounting means for said magnet for permitting reversal of the magnet upon change of the detachable contact bracket.

22. A control mechanism comprising a base, a stationary contact bracket mounted on said base, said bracket being formed so that a contact surface may be disposed on either side of said bracket, an operating arm mounted on said base and terminating short of said bracket, said operating arm oscillating laterally of said contact bracket and having its central position substantially in alignment with said stationary contact bracket, a movable contact bracket attached to said operating arm and carrying a movable contact adapted to cooperate with a stationary contact on said stationary contact bracket, said movable contact bracket being reversible upon

said operating arm so that the movable contact may cooperate with a contact surface located on either side of said stationary contact bracket.

23. A control mechanism comprising a base, an operating structure spaced from the base and pivoted thereto, a bellows mounted with its axis perpendicular to said base and engaging said operating structure for urging the same in one direction about its pivot, a spring for biasing said operating structure in the opposite direction, adjustment means fixedly secured to the base and associated with said spring, a portion of said operating structure including an operating arm extending parallel with the base and adapted to move toward and away from the base, a stationary contact bracket mounted upon said base, said bracket having a supporting portion spaced from said base and from said operating arm, a contact stud supported on the supporting portion of said bracket, said bracket being formed so that a contact surface on the contact stud may be disposed on either side of said supporting portion, a detachable contact bracket mounted on said operating arm and carrying a movable contact cooperating with said contact stud, an armature carried by said movable contact bracket, a magnet adapted to cooperate with said armature to provide snap action movement of the movable contact, and reversible mounting means for said magnet for permitting reversal of the magnet upon change of the detachable contact bracket.

24. A control mechanism comprising a base, an operating structure spaced from the base and pivoted thereto, a bellows mounted with its axis perpendicular to said base and engaging said operating structure for urging the same in one direction about its pivot, a spring for biasing said operating structure in the opposite direction, adjustment means fixedly secured to the base and associated with said spring, indicating means associated with said adjustment means for indicating the setting of said adjustment means, means including a calibrating screw interposed between said spring and operating structure for calibrating the adjustment means

5 with respect to said indicating means, a portion of said operating structure including an arm extending parallel with the base, a movable contact bracket mounted on said arm and electrically insulated therefrom, said contact bracket carrying a pair of contacts electrically connected with each other, a pair of fixed contacts on the base arranged to be bridged by said movable contacts, and means for causing said fixed and movable contacts to engage and disengage with snap action.

10 25. A control mechanism comprising a base, an operating arm spaced from the base and pivoted thereto, a bellows mounted on the base, said bellows constantly urging the operating arm in one direction about its pivot, a spring constantly engaging said operating arm for constantly urging said arm in the opposite direction about said pivot, a lever pivoted to the base and engaging said spring for varying its tension, and a cam mounted on the base and having a cam surface operatively associated with said lever whereby movement of said cam adjusts the tension of said spring, and control mechanism mounted on said base and controlled by said operating arm.

15 26. In a control device, an operating arm, resilient condition responsive means associated with the operating arm in a manner constantly urging the same in one direction, electrical switching mechanism operated by said operating arm, adjustable flexible means associated with the operating arm in a manner constantly urging the same in the opposite direction and for adjusting the condition responsive means to predetermine 20 the value of the condition at which the operating arm is actuated, said condition responsive means and said flexible means acting independently and simultaneously on said operating arm for eliminating all lost motion between said arm and each of said means, and magnetic means for 25 biasing the operating arm whereby snap action of the operating arm and of the switching mechanism is obtained by the sole cooperative action of the condition responsive means and the adjustable flexible means with the magnetic means.

45 HERBERT E. LINDEMANN.
